Primary Examiner — Kevin K Rudzinski*Assistant Examiner* — Kimberly Barnes*(74) Attorney, Agent, or Firm* — Vidas, Arrett & Steinkraus(57) **CLAIM**

The ornamental design for an architectural panel, as shown and described.

DESCRIPTION

FIG. 1 is a front-angled view of the architectural panel.

FIG. 2 is a front view of the architectural panel.

FIG. 3 is a back view of the architectural panel.

FIG. 4 is a top view of the architectural panel.

FIG. 5 is a bottom view of the architectural panel.

FIG. 6 is a right-side view of the architectural panel; and, FIG. 7 is a left-side view of the architectural panel.

The broken lines in the drawings depict portions of the architectural panel that form no part of the claimed design.
